TELEPHONE SIGNALING SYSTEM

Kenneth M. Lord, Canandaigua, and Glenn E. Warren, Honeoye Falls, N. Y., assignors to The A. E. Rittenhouse Co., Inc., Honeoye Falls, N. Y., a corporation of New York

Application June 8, 1939, Serial No. 278,122

2 Claims. (Cl. 179—86)

This invention relates to a telephone signaling system, with more particular reference to the type of telephone circuit employed in what is known as the superimposed system of ringing where a battery or direct current is superimposed on an alternating generator current, and it has for its object to afford a practical and efficient construction that will enable using a chime bar or chime element and suitable striker operating means therefor such as a solenoid, in place of the conventional vibrating ringing bell.

A further object of the invention is to afford a construction applicable to a four-party signaling circuit in which any one of the four stations is selectable from a central office, such that the solenoid or other actuating means for the chime element or signal is operated only at the one selected station while the other three signal operating means remain idle.

A more particular purpose of the invention is to provide at each station of a four-party system, where a direct current can be superimposed on an alternating current, a flow-controlling device such for instance as a copper oxide rectifier in series with the solenoid or other signal-actuating means so that when one ringing key is operated to select and signal a particular station, the current, which travels from one side of the line to ground through two of the stations will be permitted to pass freely through the solenoid at only the one selected station, the direct current through the other station on the same side of the line being retarded by the copper oxide rectifier to such an extent as to render the solenoid at that station idle.

To these and other ends, the invention consists in the construction and arrangement of parts that will appear clearly from the following description when read in conjunction with the accompanying drawing, the novel features being pointed out in the claims following the specification.

In the drawing:

Fig. 1 is a diagrammatic view of a conventional four-party superimposed system of signaling, showing the circuit arrangement at each of the four stations and the general plan of ringing keys at the central station;

Fig. 2 is an enlarged sectional view on the line 2—2 of Fig. 1 showing the construction and arrangement of the solenoid striker mechanism and chime bars;

Fig. 3 is a detail sectional view of one of the copper oxide rectifiers;

Fig. 4 is a diagrammatic view showing the 55

symmetrical form of current wave produced by the alternating generator, and

Fig. 5 is a similar view showing the form of the alternating wave as modified by the superimposed direct battery current.

Referring more particularly to the drawing in which like reference numerals refer to the same parts throughout the several views, the circuit shown includes four stations, stations Nos. 1 and 2 being connected between one side of the line 11, known as the "tip," and ground, and stations Nos. 3 and 4 being connected between the other side of the line 12, known as the "ring," and ground. The line is adapted to be connected with the central office through the conventional plug and jack 13 and 14 respectively, while 1, 2, 3 and 4 designate the respective ringing keys at central for signaling the corresponding stations.

The alternating generator is indicated at G, and it is connected through battery A to the ringing keys 1 and 3 to carry the positively biased current to opposite sides of the line, and generator G is also connected through battery B to ringing keys 2 and 4 to carry the negatively biased current to opposite sides of the line respectively. The batteries A and B act to superimpose their current on the alternating current and to shift the wave of the latter in a positive or negative direction, depending upon which ringing key is operated and the battery connected thereto. The alternating generator is also connected to ground and to the opposite sides of the line through the ringing keys as shown.

Fig. 1 shows the sine-wave form of the alternating current produced by the generator before passing through one of the batteries, the potential wave being symmetrical above and below the zero axis, while in Fig. 2 is illustrated the form of wave after the direct battery current is superimposed on the alternating current by passing the latter through a battery, resulting in pulsations that extend to a greater extent above the zero axis and to a lesser extent below the zero axis than the alternating current alone. Fig. 2 shows the effect where the alternating wave has been shifted in a positive direction by the battery current, and when shifted in a negative direction, the corresponding increased wave would be below the zero axis and the decreased wave above the zero axis.

At each station there is provided a relay 15, induction coil 16, condenser 17, telephone handset 18, and the terminal plate 19, in accordance with known practice in the art. Each relay is connected in series with its condenser across the

two sides of the line, so that the alternating potential between the two sides of the line will cause the condenser to pass alternating current to its relay, so that the relay contacts are closed at all stations when any ringing key is operated.

The present invention has to do with the arrangement at each station of a signal such as a chime bar and means for operating the signal or striking the chime bar such as a solenoid, together with a current flow-controlling device which acts to render the current ineffective when traveling in one direction on a given side of the line, and thus permits the current to operate only one solenoid and signal on one side of the line for each ringing key.

This is accomplished in the arrangement shown by providing in the conductor 20, which leads from the "tip" side of the line 11 to ground through the relay 15, a solenoid 21 and in series therewith a current flow-controlling device preferably in the form of a copper oxide rectifier 22. The parts just referred to are duplicated at each station so that it is unnecessary to describe more than one, and as appears from the drawing, the solenoid and rectifier at stations Nos. 1 and 2 are between the "tip" side of the line and ground, the rectifiers being arranged oppositely so that each one permits free passage of direct current in one direction only, and retards the passage of direct current in the opposite direction, while the solenoid and rectifier at stations Nos. 3 and 4 are between the "ring" side of the line and ground, and the rectifiers also oppositely arranged so as to permit free passage of current and operation of the solenoid when direct current is traveling in one direction only.

The rectifier shown, which is illustrated in detail in Fig. 3, is of the type consisting of a series of copper washers 23, each having a copper oxide coating 24 on one side thereof, the disks being separated by lead washers 25 and all assembled and held on a suitable sleeve 26. It will be understood that the copper oxide coating appears on one side only of the copper washers, and current passes freely through such a unit only in the direction from the oxide coating to the copper base or washer, whereas when current is traveling in the opposite direction, substantial resistance is offered which, in the present installation, is sufficient to retard the direct current to a point where it will not operate the solenoid 21.

With this explanation, it will be understood that by arranging the rectifiers at stations Nos. 1 and 2 oppositely, the direct current from ringing key 1 or ringing key 2 will operate only one of the solenoids because the rectifier at the other station will offer sufficient resistance to the direct current to prevent the solenoid being operated at that station. While there is a slight amount of current in the opposite direction for a portion of the cycle, as indicated by the shaded portion of the curve below the line in Fig. 5, this is for less than half the cycle and the current is of insufficient value to operate the solenoid at the other of the two stations.

In the structure shown, the solenoid 21, see Fig. 2, controls the plunger 27 carrying strikers 28 at its opposite ends which travel through openings 29 in the resonance chambers 30 and engage chime bars or chime elements 31 mounted in said resonance chambers.

In operation, when the current is in the proper direction to operate the solenoid 21, its plunger is moved upwardly to strike the top chime bar 31, and upon opening the signaling circuit at cen-

tral, the solenoid is deenergized and plunger 27 drops by gravity so that its lower striker engages the lower chime bar 31 after which the spring 32 returns the plunger to normal position, removing the striker from engagement with the lower chime bar. Thus a double note or chime signal is given whenever it is desired to select a signal and particular station.

In the operation of the circuit as shown, assuming that it is desired to signal station No. 1, ringing key 1 is actuated, permitting the alternating current with the positive battery current superimposed thereon to pass to the "tip" side 11 of the line and thence through the solenoid, rectifier and relay at station No. 1 to ground, the arrangement of the rectifier at station No. 1 being such as to permit free passage of the alternating current with superimposed positive battery current, and thereby operate the solenoid and chime bars.

At the same time, the current attempts to travel similarly at station No. 2 but the rectifier at that station is oppositely arranged, and prevents passage of the positively biased current, while such current as may pass through the rectifier at station No. 2 has insufficient value to operate the solenoid, and it remains idle.

To signal station No. 2, ringing key 2 is operated, causing an alternating current with a negatively superimposed battery current to pass through the circuits at stations Nos. 1 and 2, and by reason of the relation of the rectifiers, such current passes freely only at station No. 2, actuating its solenoid and chime signal while the one at station No. 1 remains idle.

It will be understood that when ringing keys 1 or 2 are operated, the current travels from the "tip" side of the line through the respective station circuits to ground, and there is not sufficient potential on the "ring" side of the line to operate stations Nos. 3 and 4. These are connected between the "ring" side of the line and ground and are subject to operation when ringing key 3 or 4 is operated, similarly as already described with respect to stations Nos. 1 and 2.

While the invention has been described with reference to a particular embodiment, it is not limited to the details and arrangement shown, and this application is intended to cover such modifications or adaptations as may come within the purposes of the invention or the scope of the following claims.

We claim:

1. In a superimposed signaling system for a telephone circuit including a plurality of subscribers' stations, a central station, signaling circuits connecting the central station with the subscribers' stations, and means at the central station for feeding a direct current superimposed on an alternating current over said signaling circuits from the central station to the subscribers' stations, the combination with a chime signal including a chime element and resonance chamber at each subscriber's station, of a solenoid at each subscriber's station having a plunger carrying a striker engageable with said chime element, said solenoid being in the said subscriber's circuit and operated by said signaling current from the central station, a rectifier interposed in the circuit at each subscriber's station in series with said solenoid and acting to permit free passage of direct current and consequent operation of the solenoid when the direct current is traveling in one direction and to prevent passage of an effective amount of current and consequently render

said solenoid idle when the direct current is traveling in the opposite direction, said rectifiers being oppositely arranged at the two stations whereby the solenoid and chime signal may be selectively operated at any subscriber's station by means of current from the central station.

2. In a superimposed signaling system for a telephone circuit including four subscribers' stations, a central station, signaling circuits connecting the central station with the subscribers' stations, and means at the central station for feeding a direct current superimposed on an alternating current over said signaling circuits from the central station to the subscribers' stations, the combination with a chime signal including a chime element and resonance chamber at each subscriber's station, of a solenoid at each subscriber's station having a plunger carrying a striker engageable with said chime element, said solenoid being in the said subscriber's circuit 15 and operated by said signaling current from the

central station, a rectifier interposed in the circuit at each subscriber's station in series with said solenoid and acting to permit free passage of direct current and consequent operation of the solenoid when the direct current is traveling in one direction and to prevent passage of an effective amount of current and consequently render said solenoid idle when the direct current is traveling in the opposite direction, the solenoid and rectifier at two of the stations being connected between one side of the line and the ground and the solenoid and rectifier at the remaining two stations being connected between the other side of the line and the ground, and the rectifiers being oppositely arranged at each of the two stations on one side of the line whereby a solenoid and chime signal may be selectively operated at any subscriber's station by means of current from the central station.
